(57) **CLAIM**

The ornamental design for a 4 tier stackable and expandable mesh shoe rack, as shown and described.

DESCRIPTION

FIG. 1 is a perspective view of a 4 tier stackable and expandable mesh shoe rack showing my new design;
FIG. 2 is a perspective view of one thereof stacked atop another thereof, showing connectors;
FIG. 3 is a perspective view of one thereof connected to another thereof by one tier thereof;
FIG. 4 is a front view thereof;
FIG. 5 is a back view thereof;
FIG. 6 is a left side view thereof;
FIG. 7 is a right side view thereof;
FIG. 8 is a top view thereof; and,
FIG. 9 is a bottom view thereof.

The broken lines in the drawing depict environmental subject matter only and form no part of the claimed design.
